UNITED STATES PATENT OFFICE.

PAUL S. MILLICE, OF HAMILTON, OHIO, ASSIGNOR TO FIRE-PROOF FURNITURE AND CONSTRUCTION COMPANY, OF NEW YORK, N. Y., A CORPORATION OF NEW YORK.

LOCKING MECHANISM FOR SUPERPOSED DRAWERS.

1,073,274.

Specification of Letters Patent. Patented Sept. 16, 1913.

Application filed December 28, 1910. Serial No. 599,651.

To all whom it may concern:

Be it known that I, PAUL S. MILLICE, a citizen of the United States, residing at Hamilton, in the county of Butler and State 5 of Ohio, have invented certain new and useful Improvements in Locking Mechanism for Superposed Drawers, of which the following is a specification.

My invention relates to locking mechanism 10 for superposed drawers, applicable to the superposed drawers for instance of vertical filing cabinets and desks, or the like, and especially intended for use in articles of this character made of metal. I have illustrated 15 the same applied to a vertical filing cabinet of metal construction.

In the selling of articles of this character some customers desire the same provided with locking mechanism, while others prefer the same without the locking mechanism 20 applied thereto. It is an item of considerable expense however, for a dealer to carry stock including the articles with and also without locking mechanism, and users frequently desire locking mechanisms applied 25 after purchase of the articles, and it is one of the objects of my invention to provide a locking mechanism for the reception of which the article may be prepared in its 30 manufacture, so that the locking mechanism may be applied to the article at any time without the necessity of reconstruction, as by the simple addition of parts, in order that a dealer or customer may supply the 35 locking mechanism without the necessity of reconstruction or the employment of tools, with the exception possibly of a screw-driver for screwing the parts to be attached in place.

40 It is a further object of my invention to provide a locking mechanism in which the locking keepers for the respective drawers are connected for combined movement and may be separately automatically locked irrespective of the locked or unlocked condition 45 of the remaining drawers.

It is a further object of my invention to provide locking mechanism common to all the drawers located at the forward ends of 50 the drawers; further, to provide a connection common to the locking keepers for placing the same for instance in locking or in unlocking positions, and, further, to provide a lock operable upon the connection for

maintaining the same with the locking keepers controlled thereby in locked positions.

In the drawings: Figure 1 is an inside elevation of my improved device showing the same applied to a vertical filing cabinet with the locking mechanism in locking relation, one of the drawers shown closed and in locked relation, another shown almost closed and about to be locked, and a third shown open, the fourth drawer being removed, the vertical filing cabinet being shown in central vertical section on the line $z-z$ of Fig. 2. Fig. 2 is a front elevation of my improved device, applied to a vertical filing cabinet. Fig. 3 is an outside side elevation of the front end of the vertical filing cabinet, partly broken away, showing my improved device applied thereto, and in locked relation. Fig. 4 is a similar view, showing my improved device in unlocked relation. Fig. 5 is a rear elevation of my improved device partly broken away, the filing cabinet being shown in vertical section on the line $y-y$ of Fig. 1. Fig. 6 is a plan view of the same. Fig. 7 is a cross section of the same on the line $x-x$ of Fig. 3; and, Fig. 8 is a cross-section on the line $w-w$ of Fig. 3.

1 represents the framework of the article to which my improved device is applied, which, as stated, may be a vertical filing cabinet, desk, or the like, and is instanced as the metal framework of a metal construction upright filing cabinet, which may comprise a standard 2 shown as a front standard of the framework, which standard may be formed up of sheet metal with an outer wall 3 and an inner wall 4. The framework may be provided with a side 5, preferably removable by unscrewing the screws 6 by which it is secured to the framework.

7, 7 represents the drawers, instanced as the filing drawers of the cabinet shown, and which are arranged to slide in and out in suitable manner, as on a suspension frame 8.

9 is the front wall of the drawer shown, comprising the forward wall 10 and the rear wall 11, shown as formed up of sheet metal. The drawers are shown in superposed relation.

12 are locking dogs or keepers which are pivoted to the frame at 13, and are preferably provided with keeping faces 14 adapted to engage with the keeping parts of the

drawers, preferably at the front of the same, the keepers 12 being instances as received through recesses 15 in the rear wall 11 of the drawer-fronts. The sides of the drawers 5 are shown as provided with inwardly extending longitudinal recesses 16 which accommodate the locking keepers.

The locking dogs are connected for combined movement for bringing the dogs into locking positions, but preferably in such 10 manner as to permit the locking dogs to have independent movement for permitting the separate locking of the drawers in the case. I accomplish this preferably by an 15 upright bar 21, having connection with the locking dogs, to which bar longitudinal movement is imparted for affecting the positions of the locking dogs. There is preferably a spaced connection between the bar 20 and dogs, shown as a pin and slot connection 22, accomplished preferably by a screw 23 received through a slot 24 in the bar and threaded into the locking dog, the bar being received between the head of the screw 25 and the locking dog, and the screw being preferably a shoulder-screw, the shoulder of which is received against the locking dog for permitting ease of movement between the dog and bar. The slot 24 is preferably 30 a curved slot, substantially on the arc of swing described from the pivot of the locking dog for permitting ease of movement of the latter. A spring 25 between the locking dog and the bar normally urges the dog 35 into locking position. This spring is shown as a spiral spring, one end of which is received about the screw 26 threaded into the screw 23, and the other end of which is received about a screw 27 threaded into the 40 bar.

In the construction shown the descent of the bar brings all of the locking dogs into unlocked relation, the upper walls of the slots 24 in the bar making contact with the 45 screws 23, which are secured to the heels 28 of the locking dogs, for causing these heels to be depressed and thereby raising the keeping parts on said dogs out of range of the keeping parts on the drawers, the pivots 50 of the dogs being shown as located between the said heels and the said keeping parts thereon.

For imparting longitudinal movement to the upright bar I provide a bell-crank lever 55 31 pivoted at 32, at the angle thereof, to the framework, this pivot being shown as a releasable shoulder-screw threaded into a sleeve 33 secured in the framework.

34 is a link to which the bell-crank lever 60 is articulated by an articulation 35, shown as a shoulder-screw, the said link being also articulated to the upright bar on an articulation 36, shown as a shoulder-screw.

37 is a manually manipulated part, shown 65 as a button, articulated at 38 to the bell-

crank lever. A spring 39 may be employed for normally urging the bar into unlocking relation in the present instance, resulting in an outward movement of the button, the spring being shown as a coiled spring received about the sleeve 33 and having a hooked end 40 received about the bell-crank lever at one end, the other end 41 of the spring being received against the framework.

42 is an obstruction, shown as a part of the link 34, which is arranged to be received across the keeper 43 of a lock 44, for normally keeping the bar in locked relation, when movement of the obstruction is prevented by the keeper of said lock. This lock is preferably a spring-lock, that is, a lock having its keeper normally urged outwardly by a spring, as see the spring 45. The keeper of the lock is arranged to be held in unobstructing position by having the obstruction 42 pass in front thereof, when the locking mechanism is placed in unlocked relation. This obstruction is shown as a forwardly projecting part of the link 34, which is preferably projected laterally from the body of the link by a lateral bend 46, so as to position the obstruction at the side of the moving parts of the bell-crank lever and into range of the keeper of the lock. The push-button and escutcheon 47 of the lock are preferably received respectively through the front of the framework, as through apertures 48 49 of an escutcheon-plate 50, suitably secured to the casing as by releasable screws 51.

The parts which are shown as holding the locking mechanism in place are the screws 13, which serve as pivots for the locking dogs, and the screw 32, which serves as a pivot for the bell-crank lever. These screws have simple threaded connection with the framework, are shown as shoulder-screws, and are easily removed from their threaded apertures 52 53 in the framework, and when they are removed the entire locking dogs and bar and connected mechanisms may be removed from the frame. The lock is also easily removable if desired, by removing the screws 54 by which the lock is secured to the framework. The openings left in the escutcheon-plate may be closed if desired, or a substitute escutcheon-plate may be put in place of the one having the openings therein, by manipulating the screws 51 by means of which the escutcheon-plate is secured to the framework.

The drawers are adapted to slide above shelves 55 and the suspension frame is adapted to slide in side channel-pieces 56, secured for instance to the front and rear uprights of the framework. Access from the compartment in which a given drawer slides to the compartment above or below the same is prevented, and the locking dog 130

for any particular drawer, is removed out of range of manipulation from said compartment above or below the same.

When the connecting bar is placed for locking position of the dogs, any of the drawers desired may be closed and locked, or certain of the drawers may remain open, the locking dogs for the latter however being in such relation that when these latter 10 drawers are closed, they will also be locked without affecting the locked relation of the previously locked drawers.

The locked relation of the locking mechanism is readily secured by the mere pushing 15 in of the push-button 37, which moves the connecting bar longitudinally, instanced as an upward movement of the same. This brings the upper walls of the slots in said bar out of the obstructing relations they 20 have maintained for unlocking position of the dogs, and the springs connecting said connecting bar and the dogs draw the rear ends of said locking dogs with the locking bar, in the movement of the latter, thereby 25 bringing the locking dogs into locking positions. Each of the locking dogs however, is still free to yieldingly move against the tension of the spring, when the keeping part of the drawer is received against the keeping 30 part of the locking dog, thereby insuring instant locking of each drawer which is fully pushed in.

While I have instanced the movement of the connecting bar as an upward movement 35 for bringing the dogs into locking positions, it is obvious that a downward movement of the same may accomplish the same purpose by reversing the positions of the keeping parts on the locking dogs, and causing the 40 latter to lock by an upward movement instead of a downward movement as instanced in the drawings. Other changes may be made without departing from the spirit of my invention.

45 My improved device is exceptionally simple and easily applied, is strong and durable, and is so constructed and arranged that the same may be applied or not to the case when manufactured, as may be desired, and if not 50 applied at the time of manufacture, may be applied at any time subsequent without reconstruction.

Each of the cases manufactured, whether 55 supplied with the locking mechanism or not at the time of manufacture, is provided with the threaded apertures for receiving the pivots 13 and 32, and the screws 54 for the lock, suitable provision being preferably made in the framework for the push-button 37 and 60 escutcheon 47 of the lock, as by providing the escutcheon-plate with the openings 48, 49, the framework being provided with registering openings 57, 58, the drawers also being provided with the recesses 15 shown 65 as in the rear wall of the front 9 of the

drawer. The outward appearance of the case is the same, whether the locking mechanism be present or not, and the locking mechanism may be applied at any time by the mere insertion of the screws 13 and 32 70 and the screwing on of the lock 44. The side is readily removable for the purpose by unscrewing the screws 6.

It will be further noted that I show the locking mechanism located between the front 75 parts of the framework and drawers, thereby avoiding lost motion and avoiding further the danger of surreptitious opening of the drawers incident to old constructions where locking mechanisms are employed at 80 the rear of the drawers, and due for instance to looseness in the drawer-parts or to springing of the parts or connections between the fronts of the framework and drawers and the points at which said locking mechanisms 85 in said old constructions are located, all of which objections are removed in my improved device.

Having thus fully described my invention, what I claim as new and desire to secure by Letters Patent is:

1. In a metal filing cabinet, the combination of a framework having superposed drawer-openings and comprising side uprights at the front of said framework 95 formed up out of sheet-metal with inner rearwardly extending flanges which form the side walls of said superposed drawer-openings, superposed drawers in said drawer-openings, locking dogs pivoted in 100 superposed relation to one of said inner rearwardly extending flanges, and coacting means at the front ends of said drawers for said locking dogs.

2. In a metal filing cabinet, the combination of a framework having superposed drawer-openings and comprising side uprights at the front of said framework formed up out of sheet-metal with inner rearwardly extending flanges which form 110 the side walls of said superposed drawer-openings, superposed drawers in said drawer-openings, locking dogs pivoted in superposed relation to one of said inner rearwardly extending flanges, coacting 115 means at the front ends of said drawers for said locking dogs, means for normally urging said dogs into locking positions, and connecting means between said dogs for causing their simultaneous operation.

3. In a metal filing cabinet, the combination of a framework having superposed drawer-openings and drawer-spaces and comprising side uprights at the front of said framework formed up out of sheet-metal 125 with inner rearwardly extending flanges which form the side walls of said superposed drawer-openings, superposed drawers in said drawer-openings, locking dogs pivoted in superposed relation to one of said 130

inner rearwardly extending flanges, coacting means at the front ends of said drawers for said locking dogs, means for normally urging said dogs into locking positions, connecting means between said dogs for causing their simultaneous operation, and separating shelves between said drawer-spaces past which said connecting means extend, said locking dogs being distanced from the horizontal planes in which said shelves are located.

4. In a metal filing cabinet, the combination of a framework having superposed drawer-openings, superposed drawers in said 15 drawer-openings, and superposed locking dogs pivoted to the inner front ends of said

framework, said drawers respectively comprising hollow sheet-metal fronts formed with a sheet-metal front wall and a sheet-metal rear wall, said sheet-metal rear walls 20 having openings therein the walls whereof form keepers for said dogs, and said dogs received in said hollows of said sheet-metal fronts.

In testimony whereof, I have signed my 25 name hereto in the presence of two subscribing witnesses.

PAUL S. MILLICE.
